REFRIGERATION APPARATUS

Leslie B. M. Buchanan, Springfield, Mass., assignor to Westinghouse Electric & Manufacturing Company, East Pittsburgh, Pa., a corporation of Pennsylvania

Application February 21, 1940, Serial No. 320,050

11 Claims. (Cl. 62—4)

My invention relates to refrigerating apparatus and particularly to an improved control therefor.

It is an object of my invention to provide an improved compensated control for refrigerating apparatus.

It is a further object of my invention to render the compensating means for a compensated control at least partially ineffective in response to abnormal temperature conditions of the media surrounding the zone to be refrigerated.

It is another object of my invention to provide an improved defrosting control for refrigerating apparatus.

It is still another object of my invention to provide an improved control for refrigerating apparatus wherein the control is compensated for changes in outside temperature and wherein defrosting is insured at those times when intermittent defrosting is automatically or manually initiated.

These and other objects are effected by my invention as will be apparent from the following description and claims taken in accordance with the accompanying drawing, forming a part of this application, in which:

Fig. 1 is a diagrammatic view of a refrigerator and control therefor illustrating my invention; and,

Fig. 2 is a fragmentary view of a manually-adjustable refrigerator control.

Referring specifically to the drawing for a detailed description of my invention, numeral 11 designates generally a refrigerator cabinet having walls 12 with heat insulation 13 therebetween, which walls surround a chamber or zone 14 to be refrigerated. A cooling element or evaporator 15 is disposed within the zone 14 to abstract heat therefrom. Vaporous refrigerant is withdrawn from the evaporator 15 through a suction conduit 16 and is compressed by a compressor 17. The compressed refrigerant is conveyed to a condenser 18 through a conduit 19 and the refrigerant is cooled and liquefied in the condenser 18. Liquid refrigerant is conveyed to the evaporator preferably through a capillary tube flow-restricting device 21 and a liquid line 22. The liquid line is larger in internal diameter than the capillary tube 21 and contains refrigerant at substantially the temperature of the evaporator 15. The liquid line 22, therefore, may be considered as a part of the evaporator 15. After refrigerant is vaporized in the evaporator 15, the cycle is repeated.

In order to control the temperature of the media in the zone 14 and to maintain it at a

substantially constant value, a temperature-control device, generally indicated at 23, is provided. The temperature-control device comprises a bulb 24, having a volatile refrigerant therein, connected through a conduit 25 to a bellows 26, so that changes in the temperature of the zone 14 will evaporate or condense more or less refrigerant in the bulb 24 and conduit 25 and cause the bellows 26 to expand or contract. 5 A spring 27 opposes the force of the bellows 26 and a switch-operating arm 28 is disposed between the spring 27 and the bellows 26. The bellows 26, spring 27 and operating arm 28 are disposed in the atmosphere surrounding the 10 refrigerator cabinet 11. The operating arm 28 is pivoted at 29 on a pin 31. The pin 31 is free to move vertically in a slot 32 in a supporting member 33. Upward movement of the arm 28 closes a pair of contacts 37 through a snap-acting device 38, and downward movement of the arm 28 opens the contacts 37 through the snap-acting device. The contacts 37 are connected to conductors 41 and 42, which conductors connect an 15 electric motor 43, which drives the compressor 17, to a source of power L₁, L₂. A cam 34 engages pivoted end 30 of the operating arm 28 and moves it vertically, thus providing a temperature adjustment, the operating arm 28 being guided by the pin 31 and slot 32. A shaft 35 is attached to the 20 cam 34 and, as shown in Fig. 2, the end of the shaft is provided with a manually-operated temperature adjusting knob 36. Rotation of the cam 34 lowers or raises the pivoted end of the arm 28, thus requiring more or less pressure in the bellows 26 to open and close contacts 37, 25 and, as a result, controlling the operation of the motor 43. A shaft 35 is attached to the cam 34 and, as shown in Fig. 2, the end of the shaft is provided with a manually-operated temperature adjusting knob 36. Rotation of the cam 34 lowers or raises the pivoted end of the arm 28, thus requiring more or less pressure in the bellows 26 to open and close contacts 37, 30 and, as a result, controlling the operation of the motor 43. A shaft 35 is attached to the cam 34 and, as shown in Fig. 2, the end of the shaft is provided with a manually-operated temperature adjusting knob 36. Rotation of the cam 34 lowers or raises the pivoted end of the arm 28, thus requiring more or less pressure in the bellows 26 to open and close contacts 37, 35 and, as a result, controlling the operation of the motor 43. A shaft 35 is attached to the cam 34 and, as shown in Fig. 2, the end of the shaft is provided with a manually-operated temperature adjusting knob 36. Rotation of the cam 34 lowers or raises the pivoted end of the arm 28, thus requiring more or less pressure in the bellows 26 to open and close contacts 37, so that the average temperature of the zone 14 at which the contacts open and close to control 40 operation of motor 43 and compressor 17, is varied.

When the temperature of the bulb 24 rises to a predetermined value, depending upon the position of the cam 34, the bellows 26 expands and forces the arm 28 upwardly to close the contacts 37 and effect operation of the motor 43, which in turn drives the compressor and effects a flow of refrigerant through the evaporator 15. When the temperature of the volatile refrigerant in the bulb 24 and conduit 25 is reduced sufficiently, the bellows 26 contracts and 45 drops the arm 28, whereupon the contacts 37 are opened, thus deenergizing the motor 43 and stopping the flow of refrigerant through the evaporator 15.

In order to compensate for changes in the 50 temperature of the media surrounding the cabi-

net 11 so as to maintain a substantially constant temperature in the zone 14, a heat-conducting clip 44 is connected between the liquid line 22 and the conduit 25 extending between the bulb 24 and bellows 26. In a control system partially filled with a volatile refrigerant, the point of the bulb 24 and conduit 25 which is at the coldest temperature will be the controlling point and, when sufficiently cold, the pressure of the volatile refrigerant corresponding thereto causes the bellows 26 to contract and open the contacts 37.

After the refrigerant-circulating mechanism has been started by the volatile liquid in the bulb 24 rising to a predetermined pressure, the refrigerant inlet conduit 22 is decreased in temperature, substantially assuming the temperature of the evaporator 15. Because of heat transfer through the heat-conducting clip 44, a point 45 on the conduit 25 where the clip 44 contacts it becomes colder than the bulb 24. The point 45, therefore, becomes the controlling point of the bellows system, and when point 45 is sufficiently reduced in temperature, the bellows 26 will contract to open the contacts 37 and thus stop the circulation of the refrigerant-circulating mechanism.

However, the liquid line 22, clip 44 and conduit 25 are all of relatively small mass and are embedded in the heat insulation 13 of the cabinet 11. The heat leakage from the media surrounding the cabinet 11, therefore, quickly heats up the parts of small mass so that the temperature at the point 45 rises above the temperature of the bulb 24. The controlling point then shifts to the bulb 24 and, as soon as the temperature in the zone 14 reaches a sufficiently high value, the pressure of the vaporizable refrigerant in the bulb 24 and bellows 26 rises sufficiently to again close the contacts 37.

As the temperature of the media surrounding the cabinet 11 rises, more heat will leak into the liquid line 22, clip 44 and portion 45 of the conduit 21 so that a lower temperature in the liquid line 22 is required to contract the bellows 26 sufficiently to open the contacts 27. The motor 43, therefore, drives the compressor 17 for a longer period of time, thus compensating for changes in outside temperature. Furthermore, as the outside temperature changes, more heat leaks into the chamber 14 and the temperature and pressure of the vaporizable refrigerant in the bulb 24 is, therefore, increased more rapidly, so that the bellows 26 is expanded and the contacts 37 are closed sooner. Compensation is similarly effected when warm foods, for example, are placed in the zone 14. At lower outside temperatures, the reverse of this operation occurs, so that the refrigerating mechanism operates less than with warmer outside temperatures.

The foregoing control system is completely described and claimed in the copending application of R. E. Tobey, Serial No. 228,072, filed September 2, 1938, now matured into Patent No. 2,192,850, dated March 5, 1940, for Refrigerating apparatus and assigned to the assignee of the present application.

As shown in Fig. 2, the various positions of the manually-adjustable knob 36 are preferably marked in degrees Fahrenheit, as a control of this type will maintain the temperature of the air in the zone 14 within a very small range.

A portion 40 of the contour of the cam 34 is so arranged that it will drop the pivot point 29 of the arm 28 sufficiently that relatively high temperatures in the zone 14 are required to close 75 form, it will be obvious to those skilled in the

the contacts 37. At this time, under normal conditions, the motor 43 drives the compressor 17 very infrequently and, as a result, the evaporator 15 rises sufficiently in temperature so that any frost which has accumulated thereon will melt. The adjusting knob 36 is provided with a position marked D corresponding to portion 40 on the cam 34 and when the adjusting knob is moved to this position, the evaporator 15 is defrosted. Such defrosting is necessary for efficient operation of the refrigerator, and while I have shown a manually-operable defrosting mechanism, it is clear that other well-known modes of defrosting are contemplated by my invention, 15 For example, those defrosting devices known in the art as "semi-automatic" or "full automatic" are also contemplated.

It has been found, however, in applying a defrosting device to a compensated control, that 20 when the temperature of the media surrounding the cabinet 11 reaches relatively high values, the evaporator 15 does not defrost even though the control is set at the defrosting position. This is because the compensating means tends to effect 25 more frequent and longer operation of the motor 43 and refrigerant is, therefore, supplied to the evaporator 15 in such quantities that it does not defrost even though the pivoted end 29 of the arm 28 of the control is dropped to the position 30 where defrosting would normally occur.

In order to overcome the aforementioned difficulty without affecting the operation of the control under normal temperature conditions, I have provided a bi-metal temperature-responsive 35 member 46 disposed in the media surrounding the cabinet 11, which is bent to the shape shown in Fig. 1 and provided with a stop 47. The bi-metal member 46 and stop 47 are so positioned that the arm 28 cannot contact the bi-metal strip 40 46 in any of the normal operating positions thereof. However, when the cam 34 and adjusting knob 36 are moved to the defrosting position and the pivoted end 29 of the lever 28 is dropped, the opposite end of the lever 28 rises. 45 If the temperature of the media outside the cabinet 11 is at a normal value, the bi-metal strip 46 is not expanded sufficiently to touch the arm 28, and defrosting is effected in a normal way. However, if the temperature of the media surrounding the cabinet 11 is at a relatively high value, for example, 90° F. or above, the bi-metal strip 46 expands so that it contacts the switch end of the lever 28 and adds bias thereto. It is, therefore, necessary for the temperature in the chamber 14 to rise a greater amount to exert sufficient pressure in the bellows to overcome the combined action of the spring 27 and the bi-metal strip 46. This increase in temperature will insure defrosting of the evaporator 15 regardless 55 of the temperature of the media surrounding the cabinet 11.

From the foregoing it will be apparent that I have provided an improved compensated control device wherein defrosting is effected and wherein defrosting is insured regardless of the temperature of the media surrounding the zone to be refrigerated. I have, furthermore, in a broader sense, provided an improved compensated control wherein the compensating means is rendered at least partially ineffective in response to abnormal temperature conditions of the media surrounding the zone to be refrigerated.

While I have shown my invention in but one form, it will be obvious to those skilled in the

art that it is not so limited, but is susceptible of various changes and modifications without departing from the spirit thereof, and I desire, therefore, that only such limitations shall be placed thereupon as are specifically set forth in the appended claims.

What I claim is:

1. In refrigeration apparatus, the combination of an insulated zone to be refrigerated, a cooling element for abstracting heat from the zone, a temperature-responsive means for controlling the temperature in the zone, means for compensating the temperature-responsive means in response to changes in the temperature of the media surrounding said zone, and means for at least partially rendering the compensating means ineffective in response to abnormal temperature conditions of the media surrounding said zone, said compensating means being entirely effective under normal temperature conditions of the media surrounding said zone.

2. In refrigeration apparatus, the combination of an insulated zone to be refrigerated, a cooling element for abstracting heat from the zone, a temperature-responsive means for controlling the temperature in the zone, means for compensating the temperature-responsive means in response to changes in the temperature of the media surrounding said zone, means for effecting intermittent defrosting of the cooling element and means for insuring said defrosting regardless of the temperature of said media surrounding the zone.

3. In refrigeration apparatus, the combination of an insulated zone to be refrigerated, a cooling element for abstracting heat from the zone, a temperature-responsive means for controlling the temperature in the zone, means for compensating the temperature-responsive means in response to changes in the temperature of the media surrounding said zone, means for effecting intermittent defrosting of the cooling element and means for insuring said defrosting when the temperature of the media surrounding the zone is at a value which would normally compensate the controlling means to such an extent to prevent defrosting.

4. In refrigeration apparatus, the combination of an insulated zone to be refrigerated, a cooling element for abstracting heat from the zone, means for circulating refrigerant through the cooling element, temperature-responsive means for controlling the operation of the refrigerant-circulating means and, therefore, the temperature in the zone, means for compensating the temperature-responsive means in response to changes in the temperature of the media surrounding the zone, means for effecting intermittent defrosting of the cooling element and means for insuring said defrosting when the media surrounding the zone is at a value which would normally compensate the controlling means to such an extent that operation of the refrigerant-circulating means would be increased sufficiently to prevent defrosting.

5. In refrigeration apparatus, the combination of an insulated zone to be refrigerated, a cooling means at least a portion of which abstracts heat from the zone, means for circulating refrigerant through the cooling means, temperature-responsive means for controlling the temperature in said zone comprising means for rendering said refrigerant-circulating means active primarily in response to the temperature of the media in said zone and inactive primarily in accordance with

the temperature of a portion of the cooling means as modified by the temperature of the media surrounding said zone, whereby the controlling means is compensated in response to the temperature of the surrounding media and the active and inactive periods of the refrigerant-circulating means are varied, means for effecting intermittent defrosting of the cooling element and means for insuring defrosting of the cooling element when the media surrounding the zone is at a value which would normally increase the active periods of the refrigerant-circulating means sufficiently to prevent defrosting.

6. In refrigeration apparatus, the combination of an insulated zone to be refrigerated, a cooling means at least a portion of which abstracts heat from the zone, means for circulating refrigerant through the cooling means, temperature-responsive means for controlling the temperature in said zone comprising means for rendering said refrigerant-circulating means active primarily in response to the temperature of the media in said zone and inactive primarily in accordance with the temperature of a portion of the cooling means as modified by the temperature of the media surrounding said zone, whereby the controlling means is compensated in response to the temperature of the surrounding media and the active and inactive periods of the refrigerant-circulating means are varied, means for effecting intermittent defrosting of the cooling element and means for insuring defrosting of the cooling element when the media surrounding the zone is at a value which would normally increase the active periods of the refrigerant-circulating means sufficiently to prevent defrosting, said last means comprising temperature-responsive means which is only effective when the temperature of the surrounding media reaches the aforesaid value.

7. In refrigeration apparatus, the combination of an insulated zone to be refrigerated, a cooling means at least a portion of which abstracts heat from the zone, means for circulating refrigerant through the cooling means, temperature-responsive means for controlling the temperature in said zone comprising means for rendering said refrigerant-circulating means active primarily in response to the temperature of the media in said zone and inactive primarily in accordance with the temperature of a portion of the cooling means as modified by the temperature of the media surrounding said zone, whereby the controlling means is compensated in response to the temperature of the surrounding media and the active and inactive periods of the refrigerant-circulating means are varied, means for effecting intermittent defrosting of the cooling element and means for insuring defrosting of the cooling element when the media surrounding the zone is at a value which would normally increase the active periods of the refrigerant-circulating means sufficiently to prevent defrosting, said temperature-responsive controlling means including an arm movable with changes in temperature and said means for insuring defrosting including a temperature-responsive device for biasing the movement of the arm in one direction.

8. In refrigeration apparatus, the combination of an insulated zone to be refrigerated, a cooling means at least a portion of which abstracts heat from the zone, means for circulating refrigerant through the cooling means, temperature-responsive means for controlling the temperature in said

zone comprising means for rendering said refrigerant-circulating means active primarily in response to the temperature of the media in said zone and inactive primarily in accordance with the temperature of a portion of the cooling means as modified by the temperature of the media surrounding said zone, whereby the controlling means is compensated in response to the temperature of the surrounding media and the active and inactive periods of the refrigerant-circulating means are varied, means for effecting intermittent defrosting of the cooling element and means for insuring defrosting of the cooling element when the media surrounding the zone is at a value which would normally increase the active periods of the refrigerant-circulating means sufficiently to prevent defrosting, said temperature-responsive controlling means including an arm movable with changes in temperature and said means for insuring defrosting including a temperature-responsive device for biasing the movement of the arm in one direction only when said surrounding media has risen in temperature to said value.

9. In refrigeration apparatus, the combination of a zone to be refrigerated, a cooling element for abstracting heat from said zone, a temperature control apparatus for controlling the temperature in the zone, means for compensating the temperature control apparatus in response to changes in refrigeration load, and means for rendering said compensating means at least partially ineffective in response to abnormal temperatures of the media surrounding said zone, said compensating means being entirely effective under normal temperature conditions of the media surrounding said zone.

10. In refrigeration apparatus, the combination of a zone to be refrigerated, a cooling element for abstracting heat from said zone, a temperature control apparatus for controlling the temperature in the zone, means for compensating the temperature control apparatus in response to changes in refrigeration load, and means for rendering said compensating means at least partially ineffective in response to abnormal temperatures of the media surrounding said zone without effecting the compensating means under normal temperature conditions of the media surrounding said zone, said compensating means being entirely effective under normal temperature conditions of the media surrounding said zone.
11. In refrigeration apparatus, the combination of a zone to be refrigerated, a cooling element for abstracting heat from said zone, a temperature control apparatus for controlling the temperature in the zone, means for compensating the temperature control apparatus in response to changes in refrigeration load, and means for rendering said compensating means at least partially ineffective in response to abnormal temperatures of the media surrounding said zone, said last means comprising a device for adding bias to said temperature control means only when the temperature of the media surrounding the zone reaches an abnormal value and said compensating means being entirely effective under normal temperature conditions of the media surrounding said zone.

LESLIE B. M. BUCHANAN.
